BABY JUMPER

Filed April 21, 1926

UNITED STATES PATENT OFFICE

ISAAC O. DUNCAN, OF NASHVILLE, TENNESSEE

BABY JUMPER

Application filed April 21, 1926. Serial No. 103,555.

This invention relates to devices for ascertaining the weight of an infant and at the same time diverting the attention and affording a soothing influence to keep the baby in good humor, and provide for a degree of exercise which is essential to a healthy development.

Primarily considered, the invention relates to an improvement on a like device for which, 10 on the 8th day of June 1926, I obtained Letters Patent of the United States, #1,587,904. In said device considerable difficulty was experienced in the assembly of the frame and when assembled, separation of the parts was 15 practically impossible. Moreover, the frame members tended to bind and spread when moving under the weight of the infant, thereby detracting from the accuracy of the device when used as scales for indicating weight. 20 Furthermore, the tendency of the frame to spread made it difficult to maintain the scale bearing plate in position.

Therefore, the present invention aims to provide a device which is free from the objections herein noted and which admits of the frame members being readily assembled and taken apart, and moving freely without any tendency to bind, so that the scale bearing plate, is not subjected to any strain tending 25 to displacement thereof, and the accuracy of the device for indicating weight assured.

While the drawings illustrate a preferred embodiment of the invention, it is to be understood that in adapting the means to meet specific needs and requirements, the design may be varied and such other changes in the minor details of construction may be resorted to within the scope of the invention as claimed, 35 without departing from the spirit thereof.

For a full understanding of the invention and the merits thereof, reference is to be had to the following description and the drawings hereto attached, in which—

45 Figure 1 is a front view of a baby jumper, embodying the invention, a portion of the sling or receiver being broken away.

50 Figure 2 is an elevational view of the frame and cooperating springs, showing the parts on a larger scale,

Figure 3 is a side view of the parts illustrated in Figure 2,

Figure 4 is a fragmentary view showing the ends of the frame members in engagement by full lines, and separated by the dotted lines, and

Figure 5 is a detail sectional view on the line 5—5 of Figure 2, looking in the direction of the arrows.

Corresponding and like parts are referred to in the following description and designated in the several views of the drawings by like reference characters.

The frame comprises complementary members 1 and 2, which are slidably related. These frame members are of similar, or like formation and inversely disposed, so that the closed end of one is at the top and the closed end of the other at the bottom, each of the members being substantially of elongated U-form and having their closed ends connected by means of a closed spiral, or helical spring 3. Each of the frame members 1 and 2 is formed of a length of wire of suitable gage, doubled upon itself to provide a yoke 4 and parallel legs which terminate in spiral or helical hooks 5. Each of the yokes 4 has a centrally disposed eye 6 in which an end of the spring 3 is engaged. The spiral hooks 5 at the free ends of the legs of one member loosely engage the legs of the companion member, thereby admitting of the members 1 and 2 having a free sliding movement. The spiral hooks 5 face in opposite directions, as indicated most clearly in Figures 2 and 3, and as a result, corresponding legs of the frame members maintain a parallel relation at all stages of adjustment of the members, and as a result, the frame members are adapted to move freely without any tendency to bind or spread, thereby assuring the accuracy of the device when indicating weight.

It is observed that the spiral or helical hooks 5 are open, and each consists approximately of a single turn or spiral, hence each hook completely encircles the adjacent leg of a frame member, thereby preventing displacement of the parts. The open formation of the spiral hooks 5 admits of the frame members being readily placed together and

- easily separated. This is indicated by the full and dotted lines in Figure 4. Upon drawing the members 1 and 2 apart, they separate readily since the hooks 5 clear each other without any manipulation other than the pulling apart of the members. The dotted lines in Figure 4 indicate one method of assembling the parts, this being effected by pressing the spiral hooks 5 of the member 2 together so as to clear the hooks of the member 1, said members being positioned so that corresponding hooks 5 are in opposition, and upon releasing the legs of the member 2 they move outwardly and the two sets of hooks 5 mutually interengage, as indicated by the full lines in Figure 4, and upon pressing the members 1 and 2 together the hooks 5 of one member slide upon the leg of the companion member.
- 20 The numeral 7 designates the plate bearing the scale graduations which coact with a pointer 8 carried by the frame member 2, whereby to indicate the weight, which is placed in a sling or receiver 9 suspended from the lower end of the frame member 2. The device is adapted to be suspended from any suitable overhead support 10, to which the upper end of the frame member 1 may be connected in any manner. The plate 7 may be attached to the frame member 1 in any preferred way.

Having thus described the invention, I claim:

In a device of the character specified, a frame comprising complementary members of approximately elongated U-form reversely disposed and slidably engaged, each of the members having its legs terminating in oppositely facing spirally formed hooks, the hooks of one member extending in an opposite direction to the corresponding hooks of the companion member, to admit of ready engagement and disengagement of the members.

45 In testimony whereof I affix my signature.
ISAAC O. DUNCAN. [L. s.]
